United States Patent Office

Des. 213,820
Patented Apr. 15, 1969

213,820

JAR

James E. Plummer, Toledo, Ohio, assignor to Owens-Illinois, Inc., Toledo, Ohio, a corporation of Ohio

Filed May 15, 1968, Ser. No. 11,952

Term of patent 14 years

Int. Cl. D9—01

U.S. Cl. D9—107

FIG. 1

FIG. 2

FIGURE 1 is an elevational view of a jar showing my new design;

FIGURE 2 is a top plan view thereof.

The side not shown is the same as the side shown.

I claim:

The ornamental design for a jar, substantially as shown and described.
